UNITED STATES PATENT OFFICE

JESSE G. KING, OF DAYTON, OHIO, ASSIGNOR TO FRIGIDAIRE CORPORATION, OF DAYTON, OHIO, A CORPORATION OF DELAWARE

REFRIGERATING APPARATUS

Application filed July 31, 1928. Serial No. 296,474.

The present invention relates to refrigerating apparatus and particularly to cooling units of such apparatus.

One of the objects of the present invention is to provide an improved construction of refrigerating element which increases its ice-freezing effectiveness.

Another object of the present invention is to provide a simple and economical arrangement of refrigerant conduits of refrigerating units which facilitate manufacture.

More specifically an object of the invention is to provide an improved arrangement of refrigerant conduits of a cooling unit so that each refrigerant conduit will be in intimate thermal contact with both a side wall and another wall of a freezing compartment or sleeve of the unit.

Further objects and advantages of the present invention will be apparent from the following description, reference being had to the accompanying drawing, wherein a preferred form of the present invention is clearly shown.

25 In the drawings:

Fig. 1 is a front view of a portion of a refrigerator cabinet with the doors open showing the improved cooling unit.

Fig. 2 is a view on a larger scale than Fig. 1 showing the front view of the cooling unit which is suspended within the cooling compartment of the cabinet, the walls of which are shown in vertical section; and

Fig. 3 is a side elevation of the cooling unit drawn to the same scale as Fig. 2.

In cooling units for household refrigerators it is desirable to provide supports, sleeves or receptacles for receiving ice trays having square outside corners and divided by grids so that, when water is frozen therein, all ice cubes produced in the trays will be substantially square and uniform. The ice tray receiving sleeves or receptacles are usually made to conform closely to the shape of the trays used to provide the most effective heat transfer path. This conformity in the shape of the sleeves also provides a compact unit. This invention is directed to increasing the amount of surface of the refrigerant ducts

which is in intimate thermal contact with the walls of the ice tray sleeves.

Referring to the drawings 10 designates a refrigerator cabinet. The cabinet provides an L-shaped food compartment 11 separated from a cooling compartment 12 by a horizontal partition 13 and a vertical partition 14. The partition 14 is provided with a flue 15 admitting relatively warm air from the food compartment 11 to the cooling compartment 12; and the partition 13 is provided with a flue 16 admitting cooled air from the compartment 12 to the compartment 11. The partition 13 supports a baffle 17 which prevents moisture, dripping from the cooling unit above, from entering the flue 16. The baffle 17 directs such moisture upon the surface of the partition 16 and the moisture is conducted away thru a drain pipe 18.

The cooling unit located within the compartment 12 includes a boiler or header 20 attached to the top walls of the cabinet 10 by bracket members 21 and 22. Condensed refrigerant is conducted to the header 20 from a compressor and condenser (not shown) thru a pipe 23 and a fitting 24. Refrigerant is admitted from the fitting 24 as needed, by a float controlled valve (not shown) of suitable construction, located in the header 20 and adapted to maintain a predetermined level of liquid refrigerant within the header. Expanded refrigerant is conducted back to the compressor thru a fitting 25 and a pipe 26. The refrigerant compressor and condenser with which the pipes 23 and 26 are connected may be located outside of the cabinet, if desired, or may be placed within a machine compartment (not shown) of the cabinet, located below the food compartment 11.

The cooling unit includes two sets of refrigerant expansion pipe loops 30 and 31 extending downwardly from the header 10 in parallel circuit relation to provide an enclosed freezing portion or space. The pipe loops 30 and 31 are flattened thruout most of their length and provided with round ends which connect with the header. One set 30 of the loops are shorter than the other set 31 and divide the central enclosed freezing

90

100

portion of the cooling unit into two freezing spaces. Each of the freezing spaces are adapted to contain supports, sleeves or ice tray receptacles 33 which rest upon horizontal leg portions 34 of the pipe loops 30 and 31. The supports or sleeves 33 are provided with relatively sharp square outside corners 35 to permit the insertion of similar shaped trays 36 for freezing substances placed therein.

10 In refrigerating elements of the sizes used in ordinary household and commercial refrigerating practice the dimensions of the refrigerant conduits and the sleeves or receptacles for the ice trays are such that it is economically impractical to bend a tube so that it can be placed in contact with adjacent sides of a rectangular sleeve. That is, there is a minimum radius on which a tube may be bent safely and economically. This radius is so large that if a portion of the tube on one side of the bend is placed in contact with one side of the rectangular sleeve, the portion of the tube on the other side of the bend is at a considerable distance from the sleeve, at so great a distance in fact that the heat transfer is negligible. In order to form a duct which can be placed in a plane perpendicular to the sides of the sleeve and which will be in intimate contact with both sides adjacent the corner, the duct loops are formed as shown in Fig. 2 with loop portions 37 extending outwardly then inwardly, hereinafter termed "a reverse bent portion." The reversed bent portions 37 are located at the corners formed by the horizontal leg portions 34 and vertical leg portions 38 of the refrigerant loops 30 and 31. This permits the bending of the tubes on any desired radius and at the same time permits contacting of the tube with both sides of the sleeve adjacent the corner. Furthermore, to increase the contacting surface between the refrigerant in the ducts and the sleeves the tubes are flattened. The flattened tubes also have an added advantage in that they can be more readily bent at the corners of the tray receiving sleeves.

While the form of embodiment of the invention as herein disclosed, constitutes a preferred form, it is to be understood that other forms might be adopted, all coming within the scope of the claims which follow.

What is claimed is as follows.

1. In a refrigerating apparatus, a cooling unit including a header, a plurality of supports disposed one above another and adapted to receive ice trays, said supports being provided with relatively sharp outside corners, and a duct extending between the supports and in intimate thermal contact with the sides forming the corner of the support above the duct.

2. In a refrigerating apparatus, a cooling unit including a support adapted to receive an ice tray, a refrigerant duct including ver-

tical and horizontal leg portions in intimate thermal contact with said support, said duct having a reverse bent portion at the connection of said leg portions.

3. In a refrigerating apparatus, a cooling unit including a support adapted to receive ice trays, said support having a bottom wall and side wall forming a relatively sharp corner and a plurality of refrigerant duct loops extending along the walls forming said corner and in intimate thermal contact therewith, said duct loops provided with a reverse bent portion adjacent the corner.

4. In a refrigerating apparatus, a cooling unit including a header, a support adapted to receive ice trays, said support having a bottom wall and a side wall forming a relatively sharp corner, and a plurality of refrigerant duct loops extending along the walls forming said corner and in intimate thermal contact therewith, said duct loops provided with a reverse bent portion adjacent the corner.

5. In a refrigerating apparatus, a cooling unit including a header and a support adapted to receive an ice tray, refrigerant duct loops arranged in parallel circuit relation with the header and enclosing said support, said duct loops including vertical leg portions formed integral with horizontal portions, each of said loops provided with reverse bent portions connecting said leg portions.

6. In a refrigerating apparatus, a cooling unit including a header, refrigerant duct loops arranged in parallel circuit relation with the header, said duct loops including vertical and horizontal leg portions, each of said loops provided with reverse bent portions located at the connection of said leg portions.

7. In a refrigerating apparatus, a cooling unit including a header, a refrigerant duct loop extending therefrom and enclosing a support adapted to receive an ice tray, said support having adjacent sides forming a relatively sharp corner, said duct loop being in a plane substantially perpendicular to the sides and secured in intimate thermal contact with both sides adjacent the corner and having a reverse bent portion located adjacent the corner of said receptacle.

8. In a refrigerating apparatus, a cooling unit including a refrigerant duct enclosing a support adapted to receive an ice tray, said support having adjacent sides forming a relatively sharp corner, said duct including portions contacting intimately with both sides adjacent the corner and a connecting portion between said contacting portions, said connecting portion including an arc of more than 90°.

9. In a refrigerating apparatus, a cooling unit including a header, a refrigerant duct loop extending therefrom and enclosing a

- support adapted to receive an ice tray, said support having adjacent sides forming a relatively sharp corner, said duct loop being in a plane substantially perpendicular to the sides and portions contacting intimately with both sides adjacent the corner and a connecting portion between said contacting portions, said connecting portion including an arc of more than 90°.
- 10 10. A refrigerating element for refrigerating apparatus comprising in combination a header forming a reservoir for liquid refrigerant and a plurality of conduits connected to the header in parallel circuit relation, said conduits being arranged to form substantially two vertical spaced apart rows to define a freezing space, some of the conduits having portions extending horizontally within the freezing space so defined.
- 15 11. A refrigerating element for refrigerating apparatus comprising in combination a header forming a reservoir for liquid refrigerant and a plurality of conduits connected to the header in parallel circuit relation, said conduits being arranged to form substantially two vertical spaced apart rows to define a freezing space, some of the conduits having portions extending horizontally through the freezing space so defined.
- 20 12. A refrigerating element for refrigerating apparatus comprising in combination a header forming a reservoir for liquid refrigerant and a plurality of loops of conduit connected to the header in parallel circuit relation, some of said loops having leg portions arranged substantially in two vertical spaced apart rows to define a freezing space, some of the loops passing horizontally through the freezing space.
- 25 13. A refrigerating element for refrigerating apparatus comprising in combination a header forming a reservoir for liquid refrigerant, a plurality of conduits connected to the header in parallel circuit relation, some of said conduits being arranged substantially in two vertical spaced apart rows to define a freezing space, and a plurality of supports for ice-making containers within the freezing space, some of the conduits having portions extending horizontally between the supports.
- 30 14. A refrigerating element for refrigerating apparatus comprising in combination a header forming a reservoir for liquid refrigerant, a plurality of loops of conduits connected to the header in parallel circuit relation, some of said loops having leg portions arranged substantially in two vertical upright spaced apart rows to define a freezing space, and some of the loops being shorter than the other loops and passing horizontally through the freezing space.

In testimony whereof I hereto affix my signature.

JESSE G. KING.
